(57) **CLAIM**

The ornamental design for a point of sale terminal, as shown and described.

DESCRIPTION

FIG. 1 is a front and left perspective view of a point of sale terminal, in accordance with our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear and right perspective view thereof; and, FIG. 9 is a reference perspective view showing the point of sale terminal disposed on a charging stand.

The broken lines in FIGS. 6 and 7 depict portions of the point of sale terminal that form no part of the claimed design.

In FIG. 9, the broken lines depict environmental structure that forms no part of the claimed design.

1 Claim, 9 Drawing Sheets
